Harry L. Duncan

ATTORNEY.

UNITED STATES PATENT OFFICE.

NOEL STATHAM, OF IRVINGTON, NEW YORK.

POCKET SAFETY RAZOR.

Application filed May 11, 1922. Serial No. 559,992.

To all whom it may concern:

Be it known that I, NOEL STATHAM, a subject of the King of Great Britain, and resident of Irvington, county of Westchester, State of New York, have made a certain new and useful Invention Relating to Pocket Safety Razors, of which the following is a specification, taken in connection with the accompanying drawing.

This invention relates especially to razors which may be of the safety razor type and comprise a sheet metal handle preferably formed with a dished up or concave resilient pivotal portion. A hinge support of sheet metal or other material may be pivotally connected with the handle as by a fixed or adjustable pivot allowing the desired amount of swinging movement between these parts which may be limited as by stops or projections. The hinge support preferably carries a hinge pin or device at some distance from the pivot about which the hinge support swings, and a resilient sheet metal blade holder may advantageously be pivoted about the hinge pin as by an integral hinge tongue on the blade support which may have cooperating gripping lips to engage and hold a safety razor blade of practically any of the usual replaceable types. The guard of sheet metal etc. may be detachably secured to the blade holder by any suitable resilient gripping members, and bifurcated tongues or portions on either of these parts may enclose and grip suitable edges on the other holder which preferably is the blade holder having a slot on its under surface; and by forming an enlarged end in this slot, a central guard retainer tongue formed on the guard may be inserted in this slot and forced along the same so as to engage and grip the adjacent edges or portions of the blade holder, the parts preferably having cooperating detents or aligning members so as to definitely and releasably hold them in operative position. The blade holder and blade when the guard has been adjusted thereto may be folded or raised into the desired projecting angular position with respect to the handle and may

be swung together with the hinge support about the handle pivot so as to give a draw cut, if desired, while when not in use the blade holder is preferably folded down adjacent the handle and swung about its pivot so as to bring the edge of the blade substantially parallel to the center line of the handle so that when the guard has been removed the blade holder may be unfolded to extend out in the plane of the handle so that the blade may be stropped in this position by hand or otherwise. When the guard is in place and the blade holder folded down against the handle in this longitudinal parallel position an extremely compact article is thus formed for traveling, for instance.

In the accompanying drawing showing somewhat diagrammatically various illustrative embodiments of this invention.

Fig. 1 is a perspective view of the razor in shaving position.

Fig. 2 is an enlarged longitudinal section thereof.

Fig. 3 is a front view showing the blade holder folded out substantially into the plane of the handle.

Fig. 4 is a corresponding view of the detached guard.

Fig. 5 is an enlarged transverse view of the blade holder taken substantially along the line 5—5 of Fig. 3, and

Figs. 6 and 7 are front and rear views of the razor in its folded position for traveling.

In the illustrative embodiment of the invention the razor handle 21 may in many cases be formed of resilient sheet metal such as brass, German silver, etc., which may be plated, if desired, with nickel, silver, or other suitable material. This handle is preferably formed with a dished up or concave resilient pivotal portion 25, as shown in Fig. 2, in which the pivot 22 may be arranged so as to secure thereto the cooperating sheet metal hinge support 18. This hinge support may have integral tongues or hinge portions 47 in which the hinge pin 17 is mounted so as to hinge to this support.

the blade holder 2 which may be similarly formed of resilient sheet metal having the bent or folded lower portion 1 so that the cooperating gripping lips 4 beyond the bent portions 3 are adapted to securely but disengagably hold between them a razor blade such as 5. As shown in Figs. 3 and 5, the blade holder may be formed with a slotted out portion 35 so as to form the hinge 10 tongue 37 bent around the hinge pin to form a hinge connecting portion on the blade holder and the tightness of this hinge joint between these parts may be readily adjusted as by screwing up the adjusting head 26 or 15 the projecting aligning nut or member 27 on the other threaded end 28 of this hinge pin. This projecting nut or a similarly projecting head on the other end of the hinge pin may, if desired, serve as stops to 20 limit the angularly swinging movement of the blade holder and connected hinge support 18 with respect to the handle since these portions may engage the handle as shown in Fig. 7 where the part 27 engages 25 the recessed portion of the handle so that further swinging movement in this direction is thus prevented after the blade holder has been swung around into the desired closely folded or shipping position. If desired, however, the hinge support 18 may 30 be formed with a rearwardly projecting aligning lug or member 24 passing over the edge of the adjacent handle portion, if desired, so as to cooperate with the stops 20 35 therein and thus form definite aligning stops to similarly limit the movement of these parts.

As shown in Fig. 1, the blade holder is 40 preferably formed with blade adjusting recesses such as 32 giving access to the rear portion of the blade so that the user can disengage or adjust the same conveniently and, as shown in Fig. 5, one or both ends 45 of the blade gripping lips 4 may be beveled at their ends so as to facilitate the lateral insertion of the blade into the holder. The guard adapted to cooperate with the razor blade may be conveniently formed of sheet metal and provided with a curved over 50 channelled edge 7 adapted to engage the skin and guide the razor blade with respect thereto and slots or apertures 16 such as shown in Figs. 2, 4 and 7 may be formed at this part of the guard, if desired. It is 55 usually advantageous to form blade aligning lugs or members, such as 8, on the guard so as to definitely position the blade edge with respect thereto and these members, which may of course be rounded off, 60 if desired, need only project very slightly beyond the surface of the guard at each end of the blade as is indicated in Figs. 2 and 4. By forming the blade holder with a guard inserting slot 35 on its under 65 face, as shown in Figs. 3 and 5, the guard

may be very readily attached to the holder when provided with a central guard retainer tongue such as 11, preferably extending somewhat out beyond the edges of this slot so that after its insertion in the enlarged slot end 36 this tongue may be pushed down inside this blade holder while the resilient lateral portions 10 of the guard engage the outside of this sheet metal member to resiliently grip the same. It is usually desirable in order to facilitate the insertion of this retainer tongue to form the lateral edges thereof with the projecting guiding ends 14 shown in Figs. 2 and 3 so that these ends can enter the slot 36 and 70 guide the tongue in its further movement. Cooperating detents such as 15, 23 may be formed on these cooperating parts as shown in Figs. 2, 4 and 5, so that when the guard tongue is pushed into the blade holder to the desired extent these detents engage and position the parts while allowing their ready disengagement when desired. In applying this guard it is advantageous to form a projecting grip such as 12 on the retainer tongue so that the user may engage it with his thumb or finger in pushing the guard into place and, as shown in Fig. 5, this grip is slightly narrower than the inserting slot 35, thus positioning the guard laterally with 75 respect to the blade holder so that the assembly of these parts is practically automatic and of course as the guard is forced home the blade aligning members thereon insure the proper positioning of the razor blade by engagement therewith as the cooperating detents engage preferably when the corners 34 of the guard inserting slot 35 are engaged between the retainer tongue and lateral portions of the guard adjacent the bends 22 of these lateral portions, see Fig. 3. In disengaging the guard the user may readily remove it from the blade holder by pushing on the grip 12 or on the projecting portion 7 of the guard, if desired, so that where the guard is removed for 80 cleaning or replacing the razor blade this may be done instantly and then the parts replaced and repositioned in a definite and reliable way without substantial loss of time. In stropping the razor blade with this device the guard may be removed and the blade holder and blade swung out into the lateral stropping position shown in dotted lines in Fig. 7 so that the blade 5 85 may then be stropped by hand on a razor strop or otherwise sharpened in any desired way.

This invention has been described in connection with a number of illustrative embodiments, parts, proportions, materials, devices, arrangements, and methods of manufacture, and use, to the details of which disclosure the invention is not of course to be limited, since what is claimed as new and 90

what is desired to be secured by Letters Patent is set forth in the appended claims:

1. In safety razors a sheet metal handle having a dished up resilient pivotal portion provided with stops, a sheet metal hinge support pivoted to said pivotal portion of the handle and having a projecting aligning member to cooperate with said stops, a hinge pin embraced by integral portions of said hinge support, a resilient sheet metal blade holder having an integral hinge tongue extending around said hinge pin and having resilient blade gripping lips and formed with a guard inserting slot having laterally enlarged slot ends, a removable razor blade engaged by said gripping lips and a resilient sheet metal guard having a central retainer tongue adapted to be inserted into the enlarged end slot in said blade holder and having flaring guiding ends to engage and grip the adjacent edges of the blade holder, the resilient lateral portions of said guard being formed with detents to releasably hold the guard in assembled position.

2. In safety razors a sheet metal handle having a pivotal portion provided with stops, a sheet metal hinge support pivoted to said pivotal portion of the handle and having a projecting aligning member to cooperate with said stops, a hinge pin embraced by portions of said hinge support, a resilient sheet metal blade holder having a hinge tongue extending around said hinge pin and having resilient blade gripping lips and formed with a guard inserting slot, a removable razor blade engaged by said gripping lips and a resilient sheet metal guard having a central retainer tongue adapted to be inserted into the enlarged end slot in said blade holder to engage and grip the adjacent edges of the blade holder, the resilient lateral portions of said guard being formed with detents to releasably hold the guard in assembled position.

3. In safety razors, a resilient sheet metal blade holder formed with a guard inserting slot having laterally enlarged slot ends, and a resilient sheet metal guard having blade aligning members to cooperate with and align the cutting edge of the razor blade and having a central retainer tongue adapted to be inserted into the enlarged end slot in said blade holder and having flaring guiding ends to engage and grip the adjacent edges of the blade holder, the resilient lateral portions of said guard engaging the other side of the cooperating blade holder portion and formed with detents to releasably hold the guard in assembled position.

4. In safety razors, a resilient sheet metal blade holder formed with a guard inserting slot having laterally enlarged slot ends, and a resilient sheet metal guard having bifur-

cated gripping portions formed with flaring guiding ends to engage and grip the adjacent edges of the blade holder.

5. In safety razors, a sheet metal handle, a pivotally connected hinge support, a hinge pin embraced by integral portions of said hinge support, a resilient sheet metal blade holder connected to said hinge pin and having resilient blade gripping lips and formed with a guard inserting slot having enlarged slot ends, a removable razor blade engaged by said gripping lips, and a resilient sheet metal guard having blade aligning members to cooperate with and align the razor blade and having a central retainer tongue formed with a bent up grip and adapted to be inserted into the enlarged end slot in said blade holder and grip the edges of said slot in connection with the resilient lateral portions of said guard.

6. In safety razors, a sheet metal handle, a pivotally connected hinge support, a hinge pin, a resilient sheet metal blade holder connected to said hinge pin and having resilient blade gripping lips and formed with a guard inserting slot having enlarged slot ends, a removable razor blade engaged by said gripping lips, and a resilient sheet metal guard having blade aligning members to cooperate with and align the razor blade and having a central retainer tongue adapted to be inserted into the enlarged end slot in said blade holder and grip the edges of said slot in connection with the resilient lateral portions of said guard.

7. In safety razors, a sheet metal handle, a pivotally connected resilient sheet metal blade holder having resilient blade gripping lips and formed with a guard inserting slot having laterally enlarged slot ends, a removable razor blade engaged by said gripping lips, and a detachable resilient sheet metal guard having blade aligning members to cooperate with and align the razor blade and having a central retainer tongue formed with a bent up grip and adapted to be inserted into the enlarged end slot in said blade holder and grip the edges of said slot in connection with the resilient lateral portions of said guard.

8. In safety razors, a sheet metal handle, a pivotally connected blade holder having resilient blade gripping lips and formed with a guard inserting slot having laterally enlarged slot ends, a removable razor blade engaged by said gripping lips, and a detachable resilient sheet metal guard having a central retainer tongue adapted to be inserted into the enlarged end slot in said blade holder and grip the edges of said slot in connection with the resilient lateral portions of said guard.

9. In safety razors, a holder having resilient blade gripping lips to engage a razor blade and formed with a guard in-

serting slot and a detachable resilient sheet metal guard having a central retainer tongue adapted to be inserted into the enlarged end slot in said blade holder and grip the edges of said slot in connection with the resilient lateral portions of said guard.

10. In safety razors, a blade holder hav-

ing resilient blade gripping lips to engage a razor blade and formed with a guard inserting slot and a resilient sheet metal guard having a retainer tongue adapted to be inserted into the enlarged end slot in said blade holder.

NOEL STATHAM.
